UNITED STATES PATENT OFFICE

134,858

DESIGN FOR A BADGE OR THE LIKE

Hosie P. Cameron, Beloit, Wis.

Application December 7, 1942, Serial No. 108,956

Term of patent 3½ years

To all whom it may concern:

Be it known that I, Hosie P. Cameron, a citizen of the United States, residing at Beloit, in the county of Rock and State of Wisconsin, have invented a new, original, and ornamental Design for a Badge or the like, of which the following is a specification, reference being had to the accompanying drawing, forming part thereof.

In the drawing:

Fig. 1 is a perspective view of the badge showing my new design.

Fig. 2 is a front elevational view of the badge.

I claim:

The ornamental design for a badge or the like, substantially as shown.

HOSIE PETER CAMERON.
